UNITED STATES PATENT OFFICE.

CHRIST RENNER, JR., OF INDIANAPOLIS, INDIANA.

ADJUSTABLE DEVICE FOR CARRIAGE-CANOPIES.

SPECIFICATION forming part of Letters Patent No. 245,659, dated August 16, 1881.

Application filed May 24, 1881. (No model.)

To all whom it may concern:

Be it known that I, CHRIST RENNER, Jr., a citizen of the United States, residing at Indianapolis, in the county of Marion and State of Indiana, have invented a new and useful Adjustable Device for Holding Canopies or Shades on Children's Carriages, of which the following is a specification.

My invention relates to a device for supporting a canopy or shade on children's carriages, in which an adjustable forked ball-socket on one part of the device operates in conjunction with a ball on the square end of the upper arm; and the objects of my invention are, first, to provide a ball-socket in two halves hinged together, with quartering-notches at the top to hold the ball and the square end of the upper arm firmly in any desired position; second, to provide the inner surface of the two halves of the ball-socket with a series of pin-holes to receive a pin and hold the upper arm in any position it may be set at; third, to provide a means for clamping the two hinged halves of the ball-socket on the ball when the upper arm with its canopy or shade are placed in the desired position. These objects I accomplish by the device illustrated in the accompanying drawings, in which—

Figure 1 represents a side view of the entire device attached to the back of a child's carriage. Fig. 2 is a rear elevation of the same. Fig. 3 is a vertical longitudinal section taken at the line X X of Fig. 2; and Fig. 4 is a longitudinal vertical section taken at the line X Z of Fig. 1, with one-half of the ball-socket removed.

Similar letters refer to like parts throughout the several views.

A represents a portion of the back of a child's carriage. B is the bracket part of the lower arm, C, which is secured to the carriage-back. The arm C extends upward above the top of the carriage, and is provided on its rear side with a hinge-knuckle, v, to which the lower end of the arm E is pivoted at a. The upper end, C', of the arm C is provided with the half D' of the ball-socket. This half of the ball-socket D' is provided on its side with a full notch or recess, f, which extends from the top of the part D' to about midway of the socket-shell, and the edges of said socket which come in contact with the edges of the other half, D, are

provided with notches f', one-half as wide as the notch f, which, together with the half-notches f² in the half D, make full notches to admit the square part g of the upper arm to be adjusted 55 therein. The inner surface of the part D' is provided with pin-holes r' r' and one-half of the pin-hole r², the other half of the pin-hole r² being in the half D of the socket. The inner surface of the part D is also provided with a continuation of this row of pin-holes, as shown at r³ r⁴, Fig. 3.

In Fig. 4 a cross-row of pin-holes are shown. This row of holes r⁵ r⁶ r⁷ r² r⁸ r⁹ r¹⁰ are formed one-half in the part D and the other half in the 65 part D' of the socket—that is, they are formed at the union of the two parts. The part D of the ball-socket has a downward-projecting arm, E, with hinge-knuckles v' v', which are, as before described, pivoted to the knuckle v by the 70 pin or bolt a. The two arms C' and E are each provided with a bolt-hole, in which the clamping-bolt b operates.

The ball F is provided with the upward-projecting arm H, and the lower end of said arm 75 H is made square to fit in the recesses f f' f² f³, as desired. The arm H and ball F have a vertical hole, i, with a slotted opening, I, above the square part g. In this hole is first inserted the spring P, then the pin R, which may be 80 round or square, and the handle G for raising or lowering the pin. The lower end, B', of the pin fits in any one of the holes r' r' r² r³ r⁴ r⁵ r⁶ r⁷ r⁸ r⁹ r¹⁰, and is designed to prevent the arm 85 H H' and its canopy or shade from working out of position, even though the binding-screw b and its nut d may become loose.

In setting up and operating my improved adjustable canopy or shade support the part B is made fast to the carriage, the bolt b is loosened, and the ball F inserted in the socket D 90 D'. The arm H is then adjusted into the desired position, with its square part g in the center, between the ends of all the recesses f f' f² f³, the end R' of the pin resting in the hole r² 95 in the center of the bottom of the socket. The binding-screw b d is then made fast, and the device is in the position shown in Figs. 1 and 2. If it is desired to tilt the arm H', to which the canopy (not shown) is attached, forward, 100 then the binding-screw b d is loosened, the pin R' is raised, and the square part g of the arm

H is tilted forward into the full notch f of the part D'. The pin R' may be then inserted in the hole r^3 or r^4 , as desired, and the binding-screw b d made fast, thus holding the arm H H' in the position shown in dotted lines in Fig. 1. If a side tilt is required for the canopy, the same operation is repeated; but the square part g of the arm H is tilted sidewise into the side recess, f' or f^3 , as desired. If tilted into the recess f' and made fast, the arm H H' is inclined sidewise, as shown in dotted lines in Fig. 2.

Having thus fully described my invention and its mode of operation, what I claim as new, and desire to secure by Letters Patent, is—

1. The arm C, with fastening-bracket B below, and provided with a hinge-knuckle, v , an upward-extending part, C', and the half D' of the ball-socket, said socket being provided with the full recess f and the two half recesses or notches f' f^3 , and further provided with the holes r r' and the half-holes r^5 r^6 r^7 r^2 r^8 r^9 r^{10} ,

(more or less,) combined with the half D of the ball-socket, having similar holes, r^3 r^4 , and half-holes to correspond with those in the part D', 25 the arm E, with hinge a , the binding-screw b and nut d , substantially as shown and described.

2. In combination with the two halves D D' of the socket, constructed as described, the ball F, with arm H, having square part g , and the pin R R', substantially as specified. 30

3. The two halves D D' of the socket, having recess f to receive and hold at various angles the square end g of the arm H, combined with the ball F, the pin-hole r and pin R R', substantially as specified. 35

In testimony whereof I have signed my name to this specification in the presence of two subscribing witnesses.

CHRIST RENNER, JR.
